Primary Examiner — Robert M Spear*Assistant Examiner* — Ryan Harvey(74) *Attorney, Agent, or Firm* — Thomas | Horstemeyer, LLP(57) **CLAIM**

The ornamental design for stationary bike, as shown and described.

DESCRIPTION

FIG. 1 is a perspective view of my new stationary bike; FIG. 2 is a front elevational view of my new stationary bike of FIG. 1;

FIG. 3 is a rear elevational view of my new stationary bike, opposite that of FIG. 2;

FIG. 4 is a side elevational view of my new stationary bike of FIG. 1;

FIG. 5 is a side elevational view of my new stationary bike from a side opposite that of FIG. 4;

FIG. 6 is a top view of my new stationary bike; and,

FIG. 7 is a bottom view of my new stationary bike.

In the drawings, the broken line showing of portions of the stationary bike illustrates environmental structure and forms no part of the claimed design.
